UNITED STATES PATENT OFFICE.

JOHN C. TURNER, OF DAYTON, OHIO, ASSIGNOR TO THE JOHN C. TURNER NOVELTY CO.,
OF DAYTON, OHIO, A CORPORATION OF OHIO.

MERRY-GO-ROUND.

1,300,674.

Specification of Letters Patent. Patented Apr. 15, 1919.

Application filed March 29, 1917. Serial No. 158,183.

To all whom it may concern:

Be it known that I, JOHN C. TURNER, a citizen of the United States, and residing at Dayton, in the county of Montgomery and 5 State of Ohio, have invented a new and Improved Merry-Go-Round, of which the following specification is a full disclosure.

This invention relates to a merry-go-round in the nature of a toy and it proposes 10 a simple construction adapted to be built in a large part of sheet metal which will automatically perform the mechanical functions of a merry-go-round and which will afford an imitation of the movements of a 15 mounted figure.

A primary object is to provide a toy of this nature which will operate automatically by the action of gravity. Another object is to devise a simple construction for imitating 20 the movements of a mounted figure such as a jockey on a horse.

Other objects will be in part obvious from the annexed drawings and in part indicated in connection therewith by the following 25 analysis of this invention.

This invention accordingly consists in the features of construction, combination of parts, and in the unique relation of the members and in the relative proportioning 30 and disposition thereof; all as more completely outlined herein.

To enable others skilled in the art so fully to comprehend the underlying features thereof that they may embody the same by 35 the numerous modifications in structure and relation contemplated by this invention, drawings depicting a preferred form have been annexed as a part of this disclosure, and in such drawings, like characters 40 of reference denote corresponding parts throughout all the views, of which:—

Figure 1 is a perspective of a horse and jockey constructed in accordance with this invention to imitate by simple means the 45 natural movements of a man on horseback. Fig. 2 is a side elevation showing in full and in dotted lines the different relative positions of the horse and rider produced by these means. Fig. 3 is a sectional elevation through line 13—13 of Fig. 2. Fig. 4 is a vertical section of the tower of the toy. Fig. 5 is a section through line 8—8 of Fig. 4 showing the ratchet means for affording a quick uplift of the operating weight. Fig. 6 55 is a vertical section of a modified construc-

tion of car, and Fig. 7 is a horizontal section through line 10—10 of Fig. 6.

Referring to the drawings A indicates a base or stand having a stationary stem B 60 standing therefrom and terminating in a head C provided with a ratchet-notch c. This stem B has a continuation D in the form of a spiral of twisted strip metal as shown by Fig. 4 or of twisted wire as shown by D' in Fig. 6. During the descent of the weight, this continuation D or D' does not turn, but for the purpose of facilitating a quick uplift of the weight, it has a ratchet-like connection with the stationary stem B, according to the arrangement shown by Fig. 70 4. Thus, the spiral D has secured to its lower end a tubular head d which closely interfits with the head C of the stem B. A snap construction d' is secured to the tubular head d and coöperates with a notch c to 75 permit the spiral D to turn in the direction corresponding in an uplift of the weight, but not otherwise. According to the modification of Fig. 6, a flange E is secured to the stem B and carries a spring e which 80 engages a cam-like notch f in the tubular head F which is soldered to the lower end of the twisted wire D'.

The spirals D or D' are provided with heads G and G' at their upper ends; which 85 heads carry pins g that pass through cross-pieces H diametrically secured to the upper end of the non-turning casing I of Fig. 4 or the rotating casing J of Fig. 6. Spirally threaded to the spirals D and D' are weights 90 K and K' which are provided with handles k whereby these weights may be uplifted. These handles project through elongated slots k' in the walls of the casings I and J. In the case of Fig. 4, the weight is provided 95 with an aperture so that it may slide up and down the rod L which is rigidly attached to the turn table M through the intermediary of a flange l which is secured rigidly both to the rod L and to the turn table M. 100 It will be seen that in its descent, the weight must rotate and thereby carry around the rod L and consequently the turn table M which is journaled about the stationary stem B and rests on the seat b.

The weight K is uplifted by the handle k which is detachable. According to the modification of Fig. 6, however, the handle k is permanently secured to the weight K' (which also has a lug k²) and this handle k 110

and lug k^2 project through slots k' and thereby effect the rotation of the tower or casing J during the descent of the weight. This casing in this instance is directly secured to the turn table M' so as to rotate the same.

Extending radially from the turn table are one or more driving arms N in the nature of a radial rod which at its outermost end n 10 is pivoted securely to an oscillator O. This oscillator has an upstanding arm 1 which is bent at 2 and has an extension 3 entering the figure P to support the same. This figure is in turn loosely arranged over another figure Q (here representing a horse) and the rider is provided with two pins 4 and 5 which are connected to arms 6 and 7 that in turn carry pivot axles 8 and 9 on which the rollers R and S eccentrically are pivoted. 15 These rollers in turn have pin and slot connections 10 with the oscillator O. The effect of this arrangement is to cause the figure of the rider P to move back and forth on the seat of the horse Q and the latter also moves 20 up and down in imitation of the gallop of a horse.

Without further elaboration, the foregoing will so fully reveal the gist of this invention that others can by applying current 30 knowledge readily adapt it for various applications without omitting certain features that, from the standpoint of the prior art, fairly constitute essential characteristics of

the generic or specific aspects of this invention, and therefore such adaptations 35 should and are intended to be comprehended within the meaning and range of equivalency of the following claims.

Having thus revealed this invention, I claim as new and desire to secure by Letters 40 Patent of the United States:—

1. A gravity toy combining a base; an upright spiral having a ratchet connection with said base; a turn-table freely pivoted to said base; a weight vertically slidable on said spiral; and means for enabling said weight to rotate said turn table during its descent.

2. A gravity toy combining a vertical spiral; a weight threaded thereto and vertically slidable thereon so as to be rotated thereby; a turn table; a tongue-and-slot connection between said weight and turn-table, enabling said weight to impart its rotations to said turn table during its descent; and a ratchet for permitting a free turning of said spiral when said weight is uplifted and for restraining its turning during its descent.

In witness whereof, I hereunto subscribe 60 my name, as attested by the two subscribing witnesses.

JOHN C. TURNER.
